UNITED STATES PATENT OFFICE

108,329

DESIGN FOR A SCALE

Ode D. Jennings, Schaumburg Township, Cook County, Ill., assignor to O. D. Jennings & Company, Chicago, Ill., a corporation of Illinois

Application February 27, 1937, Serial No. 67,908

Term of patent 14 years

To all whom it may concern:

Be it known that I, Ode D. Jennings, a citizen of the United States, residing in Schaumburg Township, in the county of Cook and State of Illinois, have invented a new, original, and ornamental Design for a Scale, of which the following is a specification, reference being had to the accompanying drawing forming a part thereof.

Fig. 1 is a front perspective view of a scale, showing my new design; and

Fig. 2 is a side perspective view thereof.

The dominant feature of my design consists in the portion shown in full lines.

I claim:

The ornamental design for a scale, as shown and described.

ODE D. JENNINGS.
